SELF-SERVICE REFRIGERATED SHOWCASE

Karl Albert Weber, Brentwood Heights, Calif.,
assignor to Weber Showcase & Fixture Co., Inc.,
Los Angeles, Calif., a corporation of Delaware

Application July 10, 1950, Serial No. 172,952

11 Claims. (Cl. 62—89.5)

1

This invention relates to a new and improved self-service refrigerated showcase.

It is an object of this invention to provide a showcase wherein frozen foods, meats and other produce can be maintained on display, readily accessible to the customers with a minimum of spoilage and deterioration of the foods so displayed.

In refrigerated showcases of the type utilizing a blower or fan to insure positive air circulation and refrigeration coils or similar refrigerating means to refrigerate the circulated air, it is customary to cut off the fan or blower during defrosting of the coils to prevent circulation of warm, moist air throughout the case.

It is an object of this invention to provide means whereby the refrigeration coils or other refrigerating means are eliminated from the path of circulation of air during this defrosting period and thus insure continuous circulation of cold air throughout the case during the defrosting period.

In general, the invention comprises a display case provided with blower means, refrigerating means so positioned that air circulated by the blower means passes around the refrigerating means, a duct leading from the refrigerating means to the display bin, in the case of a single deck showcase or to the display bins in the case of a multiple deck display case, and return ducts from the display bins to the blower means. Diverting means are provided in the passage from the blower means to the refrigerating means and in the duct leading from the refrigerating means, which are in the closed position during defrosting of the refrigerating means to divert air from the blower directly into the display bin or bins by-passing the refrigerating means, said diverting means returning to the open or normal position upon the close of the defrosting period.

Other objects and advantages of this invention will be apparent from the following specification.

Referring now to the drawings:

Figure 1 is a perspective view of a multiple type self-service refrigerated showcase embodying this invention.

Figure 2 is a sectional view taken along the line 2—2 of Figure 1.

Figure 3 is an exploded sectional view of the air-diverting means.

A housing 10 is formed by the front wall 12, a base 14, rear wall 16 and side walls 18 and 20. These walls are preferably insulated to facilitate maintaining a low temperature within the showcase. In this particular embodiment of this invention the showcase illustrated and hereinafter

2

described is a multiple deck showcase wherein the rear wall 16 projects above the front wall 12 and is provided with a top or canopy 22 which terminates a substantial horizontal distance from the front wall 12. A blower 24 is suitably mounted in the housing, herein illustrated as retained by the bracket 26 and the flange 28 on the rear wall 30 of the lower display bin 32 adjacent approximately the mid-point of the rear wall 16. However, it is obvious that the positioning of the blower can be altered substantially without departing from the scope of this invention.

An air duct 34 is formed by the rear wall 16 of the housing and the baffle 36. This baffle may take the form of an elongated plate parallel to the rear wall 16 and be bent at its lower extremity 38 to join with the bracket 26 and divert the air from the blower into the duct 34. At the upper portion of the housing below the canopy 22 suitable refrigerating means 40, herein illustrated as a well-known refrigerating coil, may be mounted. The air duct 34 leads air from the blower 24 through the refrigerating coil, thereby lowering the temperature of the air to a predetermined level.

In the upper portion of the housing and below the refrigerating means 40 is the upper display bin 42, which may be mounted in any suitable manner in the housing. An air passage 44 leads from the refrigerating means to the upper display bin, whereby a portion of the refrigerated air passes through air passage 44 and into said upper display bin. The air passage 44 is formed by the baffle member 46 which projects downwardly and rearwardly from the canopy 22, and a V-shaped baffle 48 which at its one extremity is substantially parallel to the baffle member 46 and at its opposite extremity is substantially parallel to the rear wall 16. The lower extremity of the baffle member 46 is bent as at 50 to divert the air in passage 44 rearwardly and is further bent upwardly as at 52 to provide an air channel between this upturned portion of the baffle member 46 and the rear wall 54 of the upper display bin 42. An L-shaped closure member 56 is pivotally mounted within the case, as herein-after will be described, so that in the open position its upper portion 58 is substantially parallel to the base 14 and projects above the upturned portion 52 of the baffle member 46, thereby dividing the air passage 44 into two separate channels, the innermost of said channels diverting a portion of the air from the refrigerating means 40 into the upper display bin 42. The remaining portion of refrigerated air passes between the upper portion 58 of the L-shaped closure member 56 and the baffle 48, and down an

air passage 60 formed between the rear wall 54 of the upper display bin 42 and the baffle 36. The portion of refrigerated air which flows into the upper display bin 42 passes between the front baffle 62 and the rear baffle 64 which are suitably spaced apart to form an air return duct 66. It is of course apparent that the front baffle 62 may be constructed of a plurality of glass plates spaced from one another to permit viewing of the contents 88 of the upper display bin. The air return duct 66 returns the refrigerated air from the upper display bin to the blower 24 through the air duct formed between the base of the display bin 42 and the air deflecting member 70, and through a continuation of this air duct 72 which comprises a funnel through which the air may return to the blower without coming into contact with the refrigerated air which is diverted through the air passage 60.

The refrigerated air passing through the air passage 60 passes around the funnel-like continuation 72 of the air duct 66 and between the lower portion 74 of the air deflecting member 70, which is suitably formed to provide an air passage between the flange 28 of the rear wall 30 of the lower display bin 32 and said lower portion 74 of deflecting member 70. This air deflecting member 70 may be mounted in the housing in any suitable manner herein shown as supported by the longitudinal brace 76 at its frontmost extremity and by the bolt 78 at its rearmost extremity, said bolt 78 also acting to space the air deflecting member a suitable distance from the flange 28 to form the above-mentioned air passage.

The air then flows downwardly into the lower display bin 32 circulating about the contents 80 of said lower display bin and returns through the air return passage 82 which is formed between the front wall 84 of the display bin 32 and the front wall 12 of the housing. The lower display bin 32 is spaced a sufficient distance from the base 14 of the showcase to provide an air channel 86 which constitutes a continuation of the air return passage 82. A similar air passage 88 returning the air from the passage channel 86 to the blower 24 is provided by spacing the rear wall 30 of the display bin 32 a sufficient distance from the rear wall 16 of the showcase. A front baffle 90 may be constructed in the same manner as the front baffle 62 to accomplish the same results, that is, reduce the spillage of refrigerated air over the front of the display case and to permit customers to view the contents of the lower display bin 32.

It is desirable to provide a mirror 92 suitably mounted by the brackets 94 and 96 below the air deflecting member 70 to reflect the contents 80 of the lower display bin, and thereby facilitate the viewing of said contents by prospective customers, in the front of the showcase. Similarly, a mirror 93 may be mounted on the baffle member 46 for the same purpose.

The baffle member 46 may be pivotally mounted to the canopy 22 as by a hinge 100 to permit the baffle member to be pivoted outwardly, thus permitting access to the refrigerating means. A fluorescent light 102 may be suitably mounted in the longitudinal support member 76 to facilitate viewing of the contents of the lower display bin. Also, a drain 104 may be provided in the air channel 86 to drain off excess moisture which may accumulate in the base of the case. It is also desirable to provide suitable drains (not shown) to the V-shaped baffle 48 and the baffle

member 46 to drain off moisture which may accumulate in these places.

It is, of course, apparent in the type of showcase heretofore described that considerable ice will form on the refrigerating means 40, and that it is necessary to periodically defrost the refrigerating means in order to maintain an efficient heat transfer. During the time in which the refrigerating means are being defrosted, it is necessary to prevent circulation of air over the refrigerating coils to prevent heated and moist air from being circulated throughout the showcase. To accomplish this result, the L-shaped closure member 56 and the closure member 106 are provided to by-pass the refrigerating means as hereinafter will be described. In the open position, the closure member 106 is held by the carrier 108 against the baffle 36, thus permitting unobstructed flow through the air duct 34. During the defrosting cycle, the closure member 106 is pivoted by the carrier 108 into a position closing off flow through the air duct 34, as best seen in Figure 3. When the closure member prevents flow through the upper portion of the air duct 34, it uncovers the opening 110 in the baffle 36, thereby diverting the air downwardly into the air passage 60. It is thus apparent that by sealing off the upper portion of the air duct 34, the blower 24 may be kept in continual operation, circulating the refrigerated air throughout the case during the defrosting cycle.

The L-shaped closure member 56 is also mounted to the carrier 108 in such a relationship to the closure member 106 that when said closure member 106 cuts off flow through the upper portion of the air duct 34 the L-shaped closure member 56 cuts off the air passage 44 from communication with the air passage 60. The lower portion 140 of the member 56 bears against the upper extremity 112 of the plate 36, while the opposite extremity is provided with inwardly turned flange 114 which is adapted to bear against the baffle member 46 at its upturned extremity.

It is preferred to provide a stop surface 116 either integral with the baffle member 46 or attached thereto against which the flange 114 may bear to insure an effective seal against the flow of air at this point. Attached to the upper portion of the carrier 108 adjacent the upper portion 58 of the L-shaped closure member 56 is a pivot member 118, which is pivotally mounted to the stationary member 120 by a pin 124. The member 120 may be mounted on the V-shaped baffle 48 or otherwise secured in the housing. A connecting rod 122 is rigidly attached to the pivot member 118 on the side of the pin 124 adjacent the rear wall 16. The connecting rod is suitably attached to the lever arm 126 which in turn is attached to a rocker 128, as seen in Figure 3. The rocker 128 is moved by the solenoid 130. Thus, when the defrosting cycle is commenced, the solenoid is energized and draws the plunger 132 towards the rear wall 16 of the housing. This motion through the rocker 128 drives the lever arm 126 upwardly with respect to the base 14 of the showcase. This upward motion of the lever arm 126 and the connecting rod 122 pivots the member 118 about the pin 124, swinging the closure member 56 into the closed position as seen in Figure 3 and as hereinbefore described, and at the same time moves the closure member 106 into the position seen in Figure 3, closing off the flow of air into the

upper portion of air duct 34 as hereinbefore described.

It is desirable to provide an enlarged area 134 in the air duct 34 opposite the opening 110 so that a surface 136 can be provided against which the closure member 106 will bear when in the closed position to provide an effective seal. The closure member 106 may also be provided with a flange 138 suitably formed to provide a seal against the flow of air when the 10 flange bears against the upper portion 112 of the plate 36. When the defrosting period is over, the solenoid 130 is automatically energized to force the plunger 132 horizontally away from the rear wall 16, and through rocker 128 draws the lever arm 126 vertically downward with respect to the base 14. This causes the plate member 118 to pivot about pin 124, carrying with it the carrier 108. When the carrier 108 is pivoted to the open position, as seen in Figure 20 2, the closure member 106 bears against the opening 110 deflecting the flow of air upwardly through duct 34, and the closure member 56 is pivoted so that the lower portion 140 bears against the rear wall of the upper display bin 42, thereby permitting flow of air through the air passage 44 into the air passage 60 to be circulated as hereinbefore described.

The operation of this device is as follows:

Air is circulated from the blower 24 through the air duct 34 to the refrigerating means 40. The refrigerated air then passes through the air passage 44. The air passage 44 is divided into two air channels by the upper portion 58 of the L-shaped closure member 56, a portion of the air passing between the L-shaped closure member 56 and the lower extremity of the baffle member 46 passing through the orifice formed between the rear wall of the upper display bin 42 and the rearmost extremity of the baffle member 46 into the upper display bin 42. The air then passes through the air return duct 64 and the funnel-like continuation 72 of this duct to the blower.

A portion of the refrigerated air passes between the U-shaped baffle 48 and the upper portion 58 of the L-shaped closure member 56 into the air passage 60. The air then passes downwardly over the funnel-like continuation 72 of air return duct 66 between the air deflected member 70 and the flange 28. The air then passes between the orifice formed by the rear wall 30 of the lower display bin and the rearmost extremity of the air deflecting member 70. The air passes over and about the produce in the lower display bin 32 and into the air return passage 82 passing under the lower display bin through the air channel 86 and behind the lower display bin through the air passage 88 and returning to the blower to be circulated.

When it is desired to defrost the refrigerating means 40, this can be done either manually or automatically. At the time the defrosting of the refrigerating means 40 is commenced, the solenoid 130 is energized, drawing the plunger 132 rearwardly. This rearward motion of the plunger 132 drives the lever arm 126 upwardly through the rocker 128. This upward motion of the lever arm 126 and the rigidly attached connecting rod 122 pivots the pivot member 118 about the screw 124. The pivoting of the member 118 moves the carrier member 108 until the flange 114 on the L-shaped closure member 56 engages the stop surface 116 on the baffle member 46. At the same time the lower portion 140 of the L-shaped closure member 56 bears against the upper portion 112 of the baffle 36, thereby cutting off any

flow of air through the air passage 44 into the upper display bin 42 and through the air passage 60. At the same time the closure member 106 is pivoted by the carrier 108 so that the flange 138 bears against the upper portion 112 of the baffle 36 and the opposite extremity of the closure member 106 bears against the surface 136 in the rear wall 16 thereby cutting off the flow of air from the air duct 34 to the refrigerating means. During this period the air is circulated by the blower through the lower portion of the air duct 34, through the opening 110 in the baffle 36 and downwardly into the air passage 60 and through the orifice formed between the rear wall of the upper display bin 42 and the rearmost extremity of the air baffle 46 into the upper display bin. The air then passes through the upper and lower display bins and through the return ducts as hereinbefore described.

It is of course apparent that the air diverting means herein described is adaptable for use in a single deck showcase by elimination of the air passage 60 and the associated ducts servicing the lower display bin.

While what hereinbefore has been described is the preferred embodiment of this invention, it is readily apparent that various changes in the size, shape and location of the component parts of this device can be resorted to without departing from the scope of this invention or the appended claims.

I claim:

1. A self-service refrigerated display case comprising: a housing, at least one open display bin disposed in said housing, air circulating means, refrigerating means, an air duct from said blower to said refrigerating means, an air duct from said refrigerating means to said display bin, and means in said air ducts for bypassing said refrigerating means during defrosting of said refrigerating means.

2. A self-service refrigerated display case comprising: a housing, at least one open display bin disposed in said housing, air circulating means, refrigerating means, an air duct from said blower to said refrigerating means, an air duct from said refrigerating means to said display bin, baffle members pivotally mounted in said air ducts to simultaneously cut off flow of air to and from said refrigerating means during defrosting of said refrigerating means.

3. A self-service refrigerated display case comprising: a housing, at least one open display bin disposed in said housing, air circulating means, refrigerating means, an air duct from said blower to said refrigerating means, an air duct from said refrigerating means to said display bin, a baffle pivotally mounted in said first mentioned air duct which in the open position permits air to flow to said refrigerating means and in the closed position diverts air into said last mentioned air duct, a baffle pivotally mounted in said last mentioned air duct which in the open position permits air to flow from said refrigerating means to said display bin and in the closed position diverts air from said first mentioned air duct into said display bins.

6. A self-service refrigerated display case comprising: a housing, at least one open display bin disposed in said housing, air circulating means, refrigerating means, an air duct from said blower to said refrigerating means, an air duct from said refrigerating means to said display bin, a baffle pivotally mounted in said first mentioned air duct which in the open position

7. A self-service refrigerated display case comprising: a housing, at least one open display bin disposed in said housing, air circulating means, refrigerating means, an air duct from said blower to said refrigerating means, an air duct from said refrigerating means to said display bin, a baffle pivotally mounted in said first mentioned air duct which in the open position

permits air to flow to said refrigerating means and in the closed position diverts air into said last mentioned air duct, a baffle pivotally mounted in said last mentioned air duct which in the open position permits air to flow from said refrigerating means to said display bin and in the closed position diverts air from said first mentioned air duct into said display bins, and means for simultaneously pivoting said baffles to the open or closed position.

5. A self-service refrigerated display case comprising: a housing, an open display case disposed in said housing, air circulating means, refrigerating means, walls defining an air duct from said air circulating means to said refrigerating means provided with an opening in one of the walls of said air duct, a pivotally mounted baffle in said air duct covering said opening when air flows to said refrigerating means, said baffle diverting air through said opening when pivoted to prevent air flowing to said refrigerating means, an air passage from said refrigerating means to said display bin, and means pivotally mounted in said air passage for directing air from said opening in said air duct into said display bin.

6. A self-service refrigerated display case comprising: a housing, an open display bin disposed in said housing, air circulating means, refrigerating means, walls defining an air duct from said air circulating means to said refrigerating means, an air passage from said refrigerating means to said display bin having a common wall with said air duct which wall is provided with an opening therein, a baffle pivotally mounted in said air duct covering said opening when air flows to said refrigerating means and diverting air through said opening when pivoted to prevent air flowing to said refrigerating means, and means in said air passage directing air into said display bin when air flows to said refrigerating means and cutting off flow through said air passage above said opening when air is diverted through said opening.

7. A self-service refrigerated display case comprising: a housing, an open display bin disposed in said housing, air circulating means, refrigerating means, walls defining an air duct from said air circulating means to said refrigerating means, an air passage from said refrigerating means to said display bin having a common wall with said air duct which wall is provided with an opening therein, a baffle pivotally mounted in said air duct covering said opening when air flows to said refrigerating means and diverting air through said opening when pivoted to prevent air flowing to said refrigerating means, and a baffle pivotally mounted in said air passage above said opening directing air into said display bin when air flows through said air duct to said refrigerating means and closing off said air passage when air is diverted through said opening.

8. A self-service refrigerated display case comprising: a housing, an open display bin disposed in said housing, air circulating means, refrigerating means, walls defining an air duct from said air circulating means to said refrigerating means, an air passage from said refrigerating means to said display bin having a common wall with said air duct which wall is provided with an opening therein, a baffle pivotally mounted in said air duct covering said opening when air flows to said refrigerating means and diverting air through said opening when pivoted to pre-

5 vent air flowing to said refrigerating means, a baffle pivotally mounted in said air passage above said opening directing air into said display bin when air flows through said air duct to said refrigerating means and closing off said air passage when air is diverted through said opening, and means for pivoting said baffles simultaneously to by-pass said refrigerating means.

9. A self-service refrigerated display case comprising: a housing, a pair of open display bins disposed one above the other in said housing, air circulating means, refrigerating means, walls defining an air duct from said air circulating means to said refrigerating means provided with an opening in one of the walls of said air duct, a pivotally mounted baffle in said air duct covering said opening when in the open position and diverting air through said opening when in the closed position, an air passage from said refrigerating means, means for dividing said air passage into two air channels, one of said air channels diverting air to each of said display bins, means pivotally mounted in said air passage for directing air from said opening in said air duct into said air channels.

10. A self-service refrigerated display case comprising: a housing, a pair of open display bins disposed one above the other in said housing, air circulating means, refrigerating means, walls defining an air duct from said air circulating means to said refrigerating means provided with an opening in one of the walls of said air duct, a pivotally mounted baffle in said air duct covering said opening when in the open position and diverting air through said opening when in the closed position, an air passage from said refrigerating means directing air to said display bins, a baffle pivotally mounted in said air passage which in the open position permits air to flow from the refrigerating means to the display bins and in the closed position diverts air flowing through said opening into said display bins.

11. A self-service refrigerated display case comprising: a housing, a pair of open display bins disposed one above the other in said housing, air circulating means, refrigerating means, walls defining an air duct from said air circulating means to said refrigerating means provided with an opening in one of the walls of said air duct, a pivotally mounted baffle in said air duct covering said opening when in the open position and diverting air through said opening when in the closed position, an air passage from said refrigerating means directing air to said display bins, a baffle pivotally mounted in said air passage which in the open position permits air to flow from the refrigerating means to the display bins and in the closed position diverts air flowing through said opening into said display bins, and means for simultaneously pivoting said baffles to the open or closed positions.
